UNITED STATES PATENT OFFICE.

JOHN B. GURY, OF ST. LOUIS, MISSOURI.

BASE FOR CLOTH-CUTTING MACHINES.

No. 901,439.

Specification of Letters Patent.

Patented Oct. 20, 1908.

Application filed December 30, 1907. Serial No. 408,560.

To all whom it may concern:

Be it known that I, JOHN B. GURY, a citizen of the United States, and a resident of the city of St. Louis and State of Missouri, 5 have invented a certain new and useful Improvement in Bases for Cloth-Cutting Machines, of which the following is a specification.

This invention relates to cloth-cutting machines, and it has for its principal objects to minimize vibration, to prevent unnecessary frictional contact of the cloth-lifting foot-plate, to provide a resilient integral cloth-lifting foot-plate, to eliminate separate 10 springs and loosely connected or separable parts, and to attain certain other advantages hereinafter more fully appearing. In machines of this character it is customary to provide a supporting foot-plate in connection 15 with a cloth-lifting device. Usually, the foot-plate is provided with antifriction rollers and has the cloth-lifting device resiliently attached thereto. In some cases the cloth-lifting devices comprise pivoted wings, and 20 in others a loose surrounding framelike member independently movable with respect to the foot-plate. In many of these devices which have parts loosely connected and independently movable, separate springs are 25 employed to hold the cloth-lifting devices in contact with the work table. Some of the devices herein referred to, and especially the frame-like lifting member, unnecessarily bear all around upon the work table, whereas 30 it is desirable and only necessary to exert a spring pressure upon the forward portion thereof. Furthermore, those devices comprise a multiplicity of unnecessary parts. 35

My invention overcomes the disadvantages 40 herein set forth, and it consists in the parts and in the arrangements and combinations of parts hereinafter described and claimed.

In the accompanying drawings, which form part of this specification and wherein 45 like symbols refer to like parts wherever they occur, Figure 1 is a side view partly in section, of a cloth-cutting machine embodying my invention; Fig. 2 is a cross-section of the foot-plate, taken on the line 2—2 of Fig. 3; 50 Fig. 3 is a top plan of the foot-plate with the supporting standard removed; Fig. 4 is a longitudinal section on the line 4—4 of Fig. 3; and, Fig. 5 is an inverted plan view of the foot-plate.

55 The machine illustrated in the drawings comprises a base or foot-plate hereinafter

more fully described. Mounted on the foot-plate is an upright standard 1. This standard has a frame 2 secured to the top thereof. On this frame 2 is mounted a motor casing 3 in which is preferably located an electric motor of any desirable type. The motor shaft 4 has a crank-arm or disk 5 secured on its end. Pivots attached to the crank-arm is a connecting link or pitman 6 which 60 in turn is pivotally attached to a rock-arm 7. This rock-arm is secured tightly upon a shaft 8 which has a second rock-arm 9 secured tightly thereon.

Pivots attached to the free end of the 70 rock-arm 9 is a reciprocating cutting blade 10. This cutting blade is arranged to slide in a groove provided therefor in the standard 1. To keep the blade from being thrown out of the groove in the standard when the 75 rock-arm 9 is rapidly oscillated during the operation of the machine, a spring 11 is attached at one end to the blade below the pivotal point thereof, and its opposite end is attached to a stud 12 on the rock-arm 9, as 80 shown in dotted lines in Fig. 1. If desired, the weight of the oscillatory and reciprocating parts may be counterbalanced by a spring 13 which may be connected at one end to the stud 12 and at its opposite end to an 85 eye or other attachment therefor on the frame 2.

A presser-foot 14 is adjustably mounted 90 on the frame 2. The presser-foot is arranged to be placed in coöperative relation to the cutting blade 10 and adapted to be adjusted for piles of cloth of different height. It is held in its adjusted positions by a set-screw 95 15. A hook 16 is secured on the motor casing and a handle 17 is attached to the frame 95 2, whereby the machine may be conveniently manipulated.

While the machine shown comprises a reciprocating cutting blade, it is to be understood that a machine having a rotary cutting 100 blade may be as well applied to the foot-plate which will now be more fully set forth. This foot-plate comprises an intermediate carrier portion 18 and outer cloth-lifting portions 19 and 20. The edge of the forward 105 cloth-lifting portion 20 is curved, and the upper faces of all of said cloth-lifting portions are rounded or inclined toward their edges. Preferably, the foot-plate and cloth-lifting portions comprise an integral casting. 110 The casting is slotted lengthwise, near and parallel to each side edge, and these slits 21

are cross-connected at their forward ends by a slit 22. Thereby, the foot-plate proper 18 constitutes a tongue portion which is integrally and resiliently attached to the rear portion of the surrounding cloth-lifting frame thus formed, as at 23.

The foot-plate or tongue portion is preferably thickened and stiffened by suitably ribbing the same on the bottom as more clearly shown at 24 in Figs. 2 and 5. Antifriction rollers 25 are provided for the foot-plate. Preferably, these rollers are mounted on spindles 26 and are arranged loosely in rectangular openings 27 provided therefor in the foot-plate. The spindles 26 are loosely fitted into notches or grooves 28 provided therefor in the bottom ribs 24 and in lugs 29 located for the purpose at the corners of the foot-plate 18. The spindles 26 are held in place by retaining clips or pieces 30 which are secured to the bottom of the foot-plate by screws 31.

To limit the upward and downward movement of the foot-plate and cloth lifting portions with respect to each other, when the machine is not in operative position upon a work-table or other flat surface, it is desirable to provide suitable stops. On the bottom of the tongue portion, at the forward edge thereof, is secured an outwardly projecting piece 32 which is arranged to contact with a boss 33 on the underside of the cloth-lifting portion 20. This limits the independent downward movement of the cloth-lifting portion and the upward movement of the tongue portion. Each of the side cloth-lifting portions 19 is provided with inwardly projecting pieces 34 which are arranged to contact with bosses 35 on the tongue portion 18 to limit the independent downward movement of the tongue portion and the upward movement of the cloth-lifting portions. Normally, these stops are properly spaced to allow of the independent movement of the tongue and cloth-lifting portions within certain bounds. To prevent endwise movement of the spindles 26, pins 36 are provided on the foot-plate adjacent to the ends thereof.

In manipulating the machine it is necessary that the front edges of the cloth-lifting frame be kept in close contact with the surface of the work table so as to always easily ride under the lowermost layer of a pile of cloth. It is not necessary nor desirable, however, that the entire edge of the frame should bear upon the table, as such extended bearing would cause an unnecessary amount of friction and wear. Furthermore, in such a case, the cloth-lifting portion would not always accommodate itself to any unevenness of the surface of the table.

By the present arrangement, the foot-plate or tongue 18 is made to assume a position approximately flush with the upper face 65 of the cloth lifting portion as shown in Figs. 2

to 5, inclusive, when it is free of the weight of the other parts of the machine. When the machine is in operative position, the weight thereof upon the foot-plate causes the front end of the same to bear downwardly until 70 the rollers contact with the work table. The rear rollers are arranged so that the rear portions of the cloth-lifting frame are always clear of the work table, whereas, the front rollers only bear thereupon when the foot- 75 plate is weighted down. The spring of the metal is sufficient to always keep the front portion of the cloth-lifting frame in contact with the work table, and permits the same to move sufficiently independent of the foot-plate to accommodate the machine to any unevenness of the surface of the table. By the integral construction shown, all loosely-connected parts and separate springs are 80 eliminated, and rattling and vibration are 85 thereby minimized or avoided.

Instead of making the cloth-lifting foot-plate of one piece, the tongue may be made separate from the cloth-lifting frame and connected thereto at the rear by a resilient 90 metal strip, if desired. It is noted that however the parts of the base are formed, the cloth-lifting portion is connected only to the rear part of the carrier portion and that the connection between them is resilient. 95

Obviously, the device admits of considerable other modifications without departing from the principle of the invention, and, therefore, I do not wish to be limited to the exact construction and arrangement shown. 100

What I claim as my invention and desire to secure by Letters Patent is:

1. A cloth-cutting machine comprising a foot-plate having an independently-movable cloth-lifting portion which is free from the 105 front part of the body of said foot plate but whose rear end is resiliently mounted on said foot plate, and a cutter and actuating mechanism therefor carried by said foot-plate.

2. A cloth-cutting machine comprising a 110 foot-plate having an independently-movable cloth-lifting portion which is free from the front part of the body of said foot plate but whose rear end is resiliently mounted on said foot plate, a cutter and actuating mechanism 115 therefor carried by said foot-plate, and anti-friction devices on said foot-plate arranged to relieve the same from the work-table.

3. A cloth-cutting machine comprising a foot-plate having an integral and resilient 120 cloth-lifting portion, and a cutter and actuating mechanism therefor carried by said foot-plate.

4. A cloth cutting machine comprising a foot-plate having an independently-movable 125 cloth-lifting portion connected thereto by an integral and resilient connection, and a cutter and actuating mechanism therefor carried by said foot-plate.

5. A cloth-cutting machine comprising a 130

foot-plate having an independently-movable cloth-lifting portion connected thereto by an integral and resilient connection, a cutter and actuating mechanism carried by said 5 foot-plate, and antifriction devices on said foot-plate arranged to relieve the same from the work-table.

6. A foot-plate for cloth-cutting machines comprising a carrier portion provided with 10 antifriction devices and also having a cloth-lifting portion integrally and resiliently connected thereto.

7. A foot-plate for cloth-cutting machines comprising a carrier portion provided with 15 antifriction devices, and an independently-movable cloth-lifting portion connected to said carrier portion by an integral and resilient connection.

8. A foot-plate for cloth-cutting machines 20 comprising a carrier portion, and an integral frame-like cloth-lifting portion resiliently connected to the rear part of said carrier portion.

9. A foot-plate for cloth cutting machines 25 comprising a carrier portion, and a frame-like cloth-lifting portion resiliently connected to the rear part of said carrier portion only.

10. A foot-plate for cloth-cutting machines comprising a carrier portion, a frame-like 30 cloth-lifting portion resiliently connected to the rear part of said carrier portion only, and antifriction devices on said carrier portion arranged to relieve the same and the rear part of said cloth-lifting portion from the 35 work-table.

11. A foot-plate for cloth-cutting machines

comprising a continuous surrounding frame-like cloth-lifting portion, and a carrier portion comprising a forwardly-extending and independently - movable tongue resiliently 40 connected to the rear cross member only of said surrounding frame.

12. A foot-plate for cloth-cutting machines comprising a continuous surrounding frame-like cloth-lifting portion, a carrier portion 45 comprising a forwardly-extending and independently-movable tongue resiliently connected to the rear cross member only of said surrounding frame, and antifriction devices on said carrier portion adapted to relieve the 50 same and rear part of said frame from the work table.

13. A foot-plate for cloth-cutting machines comprising a continuous surrounding frame-like cloth-lifting portion, and an independ- 55 ently-movable carrier portion comprising a resilient tongue within said frame, said tongue being integrally connected to the rear cross member of said frame.

14. A foot-plate for cloth-cutting machines 60 comprising an integral structure having a continuous surrounding frame-like cloth-lifting portion and a carrier portion comprising a resilient tongue extending forwardly from the rear cross member of said frame. 65

Signed at St. Louis, Missouri, this 26th day of December, 1907.
